UNITED STATES PATENT OFFICE.

SVEN JULIUS STRID, OF CHICAGO, ILLINOIS, ASSIGNOR TO FRED MATHEWS, OF CHICAGO, ILLINOIS.

RAILWAY CAR BRAKE.

Application filed February 7, 1927. Serial No. 166,479.

My present invention relates to brakes for railway cars and it has more particular reference to the manner of installing a high-power hand-brake upon a freight car of the hopper-bottom or dump-door type.

One of the primary objects of the present invention is to provide means for mounting the gearing for increasing the power in conjunction with the ratchet device that prevent the reverse movement of the gearing during the application of the brakes. I have also provided a novel manner of mounting the gearing upon the end-wall and supporting frame-work therefor. In connection with the ratchet device I have provided a housing for the gearing that is so designed that the brakeman will not have access to the ratchet devices excepting from a plane above the operating hand-wheel of the brake and thereby avoid the liability of the brakeman inserting his hand and arm though the wheel to manipulate the ratchet and thereby expose himself to injury. With the structure herein disclosed the hand-wheel is rotated upon a horizontal axis as are also the gears for increasing the power, and the pull-chain or cable that connects the gearing, etc., with the brake-rods below the car extends downwardly to an idle pulley and then substantially horizontally inwardly of the car to the brake rods. Other features of my invention are dependability of operation, durability of construction, simplicity and novelty in the arrangement of the parts, and economy in fabrication.

I prefer to carry out my invention and to accomplish the divers objects thereof in substantially the manner hereinafter fully described and as more particularly pointed out in the claims, reference being made to the accompanying drawings that form a part of this specification.

In the drawings:—

Figure 1, is a vertical elevation of an end portion of a railway car showing my improvements applied thereto with the gearing structure in edge elevation.

Figure 2, is a vertical face view of the structure illustrated in Figure 1, with the gearing structure in front elevation.

Figure 3, is a vertical elevation of a portion of the end walls and supporting structure of the car to illustrate the manner of

preparing the same for the installation of my gearing.

Figure 4, is a vertical transverse section of the gearing structure, the view being taken on line 4—4 of Figure 2, and looking in the direction indicated by the arrows.

In the drawings, which are more or less schematic, I have illustrated a preferred or typical embodiment of my invention, and in said drawings I have employed similar reference characters to designate the same parts wherever they appear through the several views.

As before stated, the railway car is preferably of the hopper-bottom or dump-door type and comprises the usual underframe, which includes the end-sill 5, which is a channel beam positioned with its web in a vertical plane and its lateral flanges extended inwardly of the car as seen in Figure 1. The body of the car, which is supported upon the underframe, is shown only fragmentally, and consists of longitudinal vertical side-walls 6 and transverse vertical side-walls 7 of considerably less height than the side walls and from the lower edges of which the hopper sheets 8 slope or incline inwardly and downwardly the desired distance to provide the hopper-bottom of the body. Because of the peculiar construction of such freight-cars it is frequently undesirable to mount the brake mast on a vertical axis in the usual manner, and I have therefore materially shortened said mast and positioned it with its axis horizontal and at a right-angle to the plane of the wall 7 of the car-body. In connection with the gearing I utilize the vertically disposed channel beam 9 to assist in mounting the gear-housing and pulley. The channel-beam 9 is vertically disposed, with its flanges extending outwardly from the car and its ends are secured respectively to the end-sill 5 and the end-wall 7 and the left-hand flange has a portion 10 cut away to permit of the insertion and mounting of a portion of the gear-structure, as seen in Figure 3.

The gear-housing preferably comprises outer and inner or front and rear castings that are suitably assembled and provide means for journaling the gear elements, which latter I prefer to employ in the form shown in Letters Patent No. 1,508,564, is-

sued September 16, 1924, to Fred Mathews, although it will be understood that other types of gearing may be employed. The inner or rear casting is somewhat of an inverted T-shape when viewed in front elevation, and consists of a horizontally elongated plate 11 the ends of which are apertured to receive the bolts or rivets for securing the plate in position and the right-hand end 10 portion projects through the cut away recess 10 in the vertically channel beam 9. A bearing is provided in the central portion of the lower edge to receive the transverse pin 12 upon which the winding pulley 13 is secured and also the large gear 14 of the gearing heretofore referred to. Above the plane of the upper edge of pulley 13 the rear plate of the housing extends outwardly over the pulley as at 15 and then continues 20 upwardly in a vertical direction to provide the flat upright extension 16 that is spaced from the wall 7 of the car and is provided with side walls 17 that extend back to the plane of the portion 11 of the housing first 25 described. A bearing 18 is provided in the upright portion 16 for the inner end of the brake-mast 19, upon which latter is mounted the pinion member 20 of the power gear. Lateral ears 21 project from the inner portion 30 of the side-walls 17 of the casting in substantially the plane of the portion 11 of the casting and are riveted to the vertical end-wall 7 of the car body and seen in Figures 1 and 2.

35 The side-wall 17 and the vertical plate 16 provide an enclosure into which the inner end of the brake-mast projects and a ratchet wheel 22 is mounted upon the latter and is engaged by pawl 23 mounting upon a transverse pin or bolt 24 inserted through the upper portion of the vertical plate 16. As will be seen in Figures 1 and 4, the front wall 16 extends above the plane of the pawl so that the latter is accessible solely from the top and sides and cannot be reached from the front. This prevents the brakeman inserting his hand and arm through the wheel 25 upon the mast for the purpose of releasing the pawl when throwing off the brake, and 45 the described construction compels him to operate the pawl from above or from the sides of the wheel.

Projecting horizontally from the inner or rear casting are segmental shaped flanges or 50 walls 26 that afford means for mounting the front or outer casting and which extend away from the end-wall 7 of the car to a plane beyond the vertical plane of the vertical plate 16, as shown in Figure 1. The 55 outer or front casting consists of a plate 27 of substantially circular outline with a radial extension 28 that extends up in front of and guards the face of the pinion 20 and said plate 27 and its extension are provided respectively with bearings for the pin 60

12 and mast 19. A flange 29 projects inwardly from the edge of plate 27 and the same is secured by rivets 30 to the segmental flanges 26 of the inner or rear casting.

The winding pulley 13 has one end of the 70 chain 31 secured to it while the opposite end of said chain is secured to the proper brake operating rod under the car. The chain extends downwardly from pulley 13 to and partly around an idle pulley 32 and then substantially horizontally inwardly of 75 the car. The pulley 32 is partly enclosed within a guard 33 that has upper and lower lugs 34 that are riveted to the adjacent flange of the vertical channel beam 9 and also has a lateral foot or lug 35 that is secured to the top flange of the channel end-sill of the underframe, thus securely mounting and bracing said pulley against the upward and inward pull of the chain during 80 the application of the brake.

What I claim is:—

1. The combination with a railway-car including an underframe and a vertical end-wall, of a brake actuating structure comprising a gear housing consisting of spaced front and rear members mounted upon said wall, a horizontally disposed brake-mast journaled in said housing members, gears mounted between said housing members and connected with said mast, a pawl and ratchet structure controlling said gearing, and an extension projecting from one of said housing members past said pawl and ratchet structures whereby the latter is inaccessible in a horizontal direction from the front of the mechanism.

2. The combination with a railway-car, of a brake actuating structure comprising a brake-mast and hand-wheel mounted at the 105 end of said car and rotatable upon a horizontal axis, gearing connected with said mast and with the brake mechanism, a pawl and ratchet structure controlling said gearing, and a housing for said gearing secured to the end of the car and provided with a portion that extends in front of and above said pawl whereby the latter is manually accessible solely around the edges of the 110 housing extension.

3. The combination with a railway-car having an end-sill, a vertical end-wall spaced above said sill, and a post mounted on said sill and extended to and secured to said wall, of a gear-housing secured to said wall and the upper portion of said post, gears rotatable upon horizontal axes within said housing, means for actuating said gears, a chain connecting said gears to the brake mechanism, and a rotatable member mounted upon said sill below said housing and connected with said post to be engaged by an intermediate portion of said chain.

4. The combination with a railway-car having an end-sill, a vertical end-wall 120

spaced above said sill, and a post mounted on said sill and extended to and secured to said wall, of a gear-housing secured to said wall and the upper portion of said post, gears 5 rotatable upon horizontal axes within said housing, means for actuating said gears, means connecting said gears to the brake mechanism and a rotatable member mounted upon said end-sill below said housing and connected with said post to be engaged by 10 an intermediate portion of said means.

Signed at Chicago, in the county of Cook, and State of Illinois, this eighth of June, 1926.

SVEN JULIUS STRID.
